UNITED STATES PATENT OFFICE.

GLENN E. McFADDEN, OF KANSAS CITY, MISSOURI.

DESIGN FOR A CHANDELIER OR SIMILAR ARTICLE.

Application filed March 18, 1927. Serial No. 21,199. Term of patent 7 years.

To all whom it may concern:

Be it known that I, GLENN E. McFADDEN, a citizen of the United States, residing at 315 East Winthrop Road, Kansas City, Missouri, have invented a new, original, and ornamental Design for a Chandelier or Similar Article, of which the following is a specification, reference being had to the accompanying drawing, forming a part hereof.

The figure in the accompanying drawing is a perspective view of a chandelier or similar article, showing my new design.

I claim:

The ornamental design for a chandelier or similar article, substantially as shown.

GLENN E. McFADDEN.
